Primary Examiner — Nathaniel D. Buckner(74) *Attorney, Agent, or Firm* — ScienBiziP, P.C.(57) **CLAIM**

The ornamental design for a wireless charging stand, as shown and described.

DESCRIPTION

FIG. 1 is a first perspective view of a wireless charging stand, showing my design.

FIG. 2 is a second perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a perspective view of the wireless charging stand showing the status when the wireless charging stand is unfolded.

The broken lines in the figures depict portions of the wireless charging stand which form no part of the claimed design.
